UNITED STATES PATENT OFFICE.

HENRY LIGHTWARDT, JR., OF PHILADELPHIA, PENNSYLVANIA.

BOOT-JACK.

SPECIFICATION forming part of Letters Patent No. 329,576, dated November 3, 1885.

Application filed August 29, 1885. Serial No. 175,612. (No model.)

To all whom it may concern:

Be it known that I, HENRY LIGHTWARDT, Jr., of the city of Philadelphia, in the county of Philadelphia and State of Pennsylvania, have invented certain new and useful Improvements in Boot-Jacks; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to boot-jacks, and has for its object to furnish an article of that class which shall not only be of the greatest utility for the purposes for which these articles are used, but which shall also be of such a construction that it may be converted, when not in use, into an article having the appearance of a double-barreled toy pistol. In carrying out these objects I have constructed the device of which I shall now proceed to fully describe the construction and operation, and the specific points of novelty in which I shall particularly point out in the claims appended thereto.

In short, my invention consists in a convertible boot-jack and imitation double-barreled pistol of the construction substantially as hereinafter described and claimed.

In the drawings, Figure 1 is a perspective view showing my invention open and in the position to be used as a boot-jack. Fig. 2 is a bottom plan view of the same in the same position as shown in Fig. 1, and Fig. 3 is a view in side elevation of the device folded or in the position to be used as an imitation double-barreled pistol or a pistol for the explosion of the well-known paper percussion pads or caps.

Like letters of reference mark the same parts in all the figures.

Referring to the drawings by letters, A A' are the two principal members of the device, each of which represents a complete single-barrel pistol, except that the handle and stock portions are in halves to cause them, when brought together by folding against each other, to form one complete handle and stock. The various portions of these members are marked,

respectively, the barrels *a a'*, the guards *b b'*, and the handles *c c'*. One of the members is provided with a lock of ordinary construction, comprising a hammer, *d*, a nipple or its substitute, *d'*, a trigger, *d''*, and suitable springs, (not shown,) being covered by a plate, *e*, which forms one leaf of a hinge, by which the two members A A' are hinged together, the other leaf, *e'*, being secured to the other member. These hinge-leaves are let into the inner sides of the members A A', so as to be flush with the surface thereof, and thereby not to interfere with the proper and close folding together of the two members. The guards *b b'* are also made flat on one side with the same object in view, and each of them has a nib or projection (marked *b² b³*) located at different parts of their respective guards, so that they will not coincide when folded, but will form, as shown in Fig. 3, points of bearing for the fingers of the user for the purpose of unfolding the device. Each of the members A A' is formed with a rectangular groove, as at *f f'*, of double the area in section of bars *g g'*, one of which is secured rigidly in each of said grooves, and when the device is folded extends into the other of said grooves, the end of said bars being shown in Fig. 3, and each bar being of a length just sufficient to fill the grooves exactly, as shown, thus giving a flush, neat finish to the device in its pistol form. The member A' is formed with a recess, *h*, to accommodate the hammer and nipple when the device is unfolded, so that in the unfolded or boot-jack position these devices will be below the surface and show no projection to mar the finish or detract from the usefulness of the device.

The operation of my invention may be described as follows: The device being in its folded or pistol form, and it being desired to convert it into a boot-jack, the user by means of the projections on the guards presses the members apart, causing them to unfold on the hinges until the position in Fig. 1 is reached. In this position the bars *g g'* stand out at right angles to the members A A', and form legs for the boot-jack. The barrels *a a'* separate, forming a wedge-shaped opening or space, *B*, which, when the handles, also separated, and forming a space, *B'*, are on the floor, forms

a boot-jack with straight members, and by pressing the separated barrels to the floor and elevating the separated handles a boot-jack with curved members is formed.

5 It will be seen that by my invention a boot-jack of double capacity is formed, which, in addition to its usefulness as such, may be converted by simply folding its members into a pistol of ornamental construction and capable of use as a toy or ornament.

Having thus described my invention, what I claim, and desire to secure by Letters Patent, is—

1. A convertible boot-jack formed of two members, A A', hinged together at $e e'$, and being provided with legs $g g'$ and guards $b b'$, for the purposes set forth.

2. The combination of members A A', hinges $e e'$, legs $g g'$, and guards $b b'$, having projections $b^3 b^3$, for the purpose set forth.

3. The combination of members A A', hinged together and having grooves $f f'$, the legs $g g'$, rigidly secured in said grooves, and the

guards $b b'$, secured to said members, respectively, for the purpose set forth.

4. A convertible boot-jack made of the form of a toy double-barreled pistol, consisting of two members, A A', each consisting of a barrel and half-handle, and each provided with a leg, which, when unfolded, forms the leg of the boot-jack, and a half-guard having a projection to assist in unfolding a device, the member A having a lock provided with a trigger, hammer, and nipple, the two members being hinged together by hinge $e e'$, one leaf of which forms the lock-plate, and the member A' being recessed to receive and contain the hammer and nipple when the device is used as a boot-jack, as set forth.

In testimony that I claim the foregoing as my own I affix my signature in presence of two witnesses.

HENRY LIGHTWARDT, JR.
